METHOD OF FREQUENCY OR PHASE MODULATION

David G. C. Luck, Haddon Heights, N. J., assignor to Radio Corporation of America, a corporation of Delaware

Application October 29, 1936, Serial No. 108,163

18 Claims. (Cl. 250—6)

My invention relates to the transmission and reception of energy at radio frequency. In particular, my invention relates to a method of modulating a carrier by first creating a phase modulated wave which in turn creates a series of modulated impulses which key a transmitter, and to a method for receiving and translating said modulated carrier. The present application is a continuation in part of my Patent No. 2,086,918, dated July 13, 1937, and assigned to the same assignee as the present application.

For faithful reproduction at the receiver of the modulated signals at the transmitter, it has heretofore been considered essential that all the circuit elements should be linear; that is, that they should respond in proportion to the intensity of the applied signal. Under this limitation it has been known for a number of years that any discrimination between desired signal and noise entering the signaling system must be the result of selectivity of the circuits involved. If the signal occupies the minimum frequency range necessary for transmission of the desired intelligence and the selectivity of the circuit used is such that it passes this signal frequency range freely but suppresses disturbances of all other frequencies, no further improvement in the ratio of signal to random noise can be hoped for, except, of course, by increasing the intensity of the transmitted signal.

The possibilities of improvement of the ratio of signal intensity to noise intensity I have found to lie in a departure from ordinary methods of amplitude modulation. I have found also that these possibilities may be extended by the use of "non-linear" circuits having an output by no means proportional to the input.

Briefly, my system contemplates the transmission of certain timing marks. The transmission of intelligences may be had without in the least depending upon amplitude modulation of the carrier. The improvement in the ratio of signal intensity to noise intensity, therefore, is obtained largely by virtue of the fact that these timing marks can be shifted over a wide range by the desired signal, but only over a definite narrow range by any noise of less amplitude than the signal. While any interference causing noise of greater amplitude than the signal is not suppressed in the operation of my system, it will be apparent that the signal-to-noise ratio is in large part improved over what is possible when using the generally accepted present-day methods.

An object of my invention is to provide means for converting a phase modulated wave into a

series of modulated impulses for the keying of a carrier frequency current.

Another object is to provide means for reconverting said impulsive keyed carrier current into a phase modulated current and for demodulating said phase modulated current.

An additional object is to provide means for operating a system of radio communication which shows an improved ratio of signal-to-static over conventional systems employing similar amounts of power.

Fig. 1 represents, in schematic outline, one embodiment of my invention applied to a transmission system,

Figs. 2 and 3 are schematic illustrations of receiving systems for receiving and demodulating the impulse modulated signals transmitted in accordance with my invention.

Fig. 4 is a circuit diagram of a carrier frequency generator,

Fig. 5 is a circuit diagram of a phase modulator,

Fig. 6 is a circuit diagram of an impulse generator,

Fig. 7 is a circuit diagram of an impulse relay,

Fig. 8 is a circuit diagram of a radio transmitter suitably arranged for keying,

Fig. 9 is a circuit diagram of a differentiator and rectifiers,

Fig. 10 is a circuit diagram of an apparatus for reconstructing the dots from impulses,

Fig. 11 is a circuit diagram of a filter, and

Fig. 12 is a circuit diagram of a phase demodulator.

If the amplitude of an oscillatory current is varied in accordance with a desired signal, the oscillation is said to be amplitude modulated. Likewise, if the frequency of an oscillatory current is varied in accordance with the signal to be transmitted, the oscillation is said to be frequency modulated. The rate of change of the phase of an oscillatory current is termed the frequency of that current. Therefore, it may be seen that a frequency modulated current may be termed a phase modulated current. The difference between the two depends upon the particular relation between the variations of the original signal and the variation of phase or frequency produced by it. The system I am about to describe may be adapted to either phase or frequency modulation.

Signal frequency currents are phase or frequency modulated. The phase or frequency modulated currents are converted into a series

of variably timed impulses which operate an impulse relay; concurrently a sinusoidal current is converted into a series of uniformly spaced impulses which also operate the impulse relay. 5 This relay is arranged to be selectively operated to the "on" condition by impulses of the variably spaced series and to the "off" condition by alternately occurring impulses of the uniformly spaced references series. The output of the 10 relay is used to key a carrier current generator which transmits a series of dots, whose duration is a function of the signal frequency currents.

The condition for a dot, of the character described in my Patent No. 2,086,918, dated July 13, 1937, to end is:

$$\frac{t}{T} - \frac{b}{2a} \cdot f(t) = n \quad (1)$$

20 where t is time of ending of n th dot, T is dot repetition period,

$$\frac{b}{2a} = m$$

25 which is depth of modulation (less than 1) and $f(t)$ is modulating wave (maximum value 1).

A phase modulated wave, of unmodulated frequency

$$\frac{1}{T}$$

30 may be defined as

$$A = A_0 \sin \left[\frac{2\pi t}{T} - \frac{2\pi B}{360} f(t) \right] = A_0 \sin \phi \quad (2)$$

35 where B is the maximum phase shift in degrees produced by the modulating signal, which varies with time in accordance with the function of $f(t)$. The phase modulated wave passes through the zero value in one particular direction whenever the angle ϕ (which is the phase of the wave) 40 has a value of any integral multiple of 2π radians. Therefore, the times when the phase modulated wave is zero are given by

$$\frac{t}{T} - \frac{B}{360} f(t) = n \quad (3)$$

45 where n is any integer.

Comparison of Equations (1) and (3) shows clearly that the instants at which a set of modulated dots stop are the same as those at which the phase modulated sine wave passes through zero. The foregoing theory, taken in conjunction with the explanation of Fig. 1, makes it clear how the passage through zero of a phase modulated wave and a synchronous unmodulated 55 wave may be used respectively to control stopping and starting instants of a normal modulated dot train.

When the modulator is inactive, both groups of impulses are equally and uniformly spaced and the impulses of each group are centrally interspersed between those of the other. When modulation is applied, one group of impulses becomes variably spaced, while the other group remains uniformly spaced. Modulation causes the 65 impulses of one group to be varied in spacing within the limits set by the adjacent impulses of the uniformly spaced group.

In Fig. 1, an embodiment of my invention is applied to a transmitter which comprises a signal source or microphone 1 whose output circuit is connected to the input of an amplifier 3. The amplifier output circuit is connected to a phase modulator 5. The phase modulator output is connected to an impulse generator 7. A constant 70 frequency generator 9 is connected to the phase

modulator 5 and to a second impulse generator 11.

The output circuits of the impulse generators 7, 11 are connected to the input of an impulse relay 13. The output of the relay 13 is connected to a keying circuit of a radio transmitter 15. The 5 transmitter is coupled to an antenna 17.

The operation of the transmitter is as follows: The amplified signal frequency currents 19 are impressed on the phase modulator to vary the phase of the carrier frequency currents which 10 are impressed on the phase modulator. The phase modulated currents 21 are converted into impulses 23 which are variably spaced or timed as a function of the phase modulation. These impulses 23 are rectified and the positive impulses 15 impressed on the impulse relay 13. The carrier frequency currents 25 are also impressed on a second impulse generator 11 to form a uniformly spaced or timed series of impulses 27 which are likewise rectified. The positive impulses are 20 also impressed on the impulse relay 13, which, operating as just described, establishes output currents 29 which are used to key the transmitter 15. The transmitter radiates dot modulated carrier waves 31.

25 Suitable receiving systems are schematically represented in Figs. 2 and 3. Referring to Fig. 2: An antenna 33 is suitably coupled to a radio receiver 35. The output of the receiver is connected to a limiter 37 which is in turn coupled to a differentiator 39. The output of the differentiator is impressed on a pair of rectifiers 41. The rectifiers are connected to dot reconstructors 43, 46 which are connected, respectively, to filters 47, 49. The output of the filters 47, 49 35 is impressed on a phase demodulation translator 51 which is connected to a signal indicator, such as a loudspeaker 53 or the like.

The operation of this receiving system is as follows: The incoming dot modulated carrier 40 wave 55 is amplified and detected by the receiver 35 which may be tuned to attenuate currents of undesired frequencies. The amplified and rectified dot modulated carrier 57 is separated from excessive impulses, caused by static and the like, 45 by the limiting action of a limiter 37. The limited dots 59 are separated into discrete positive and negative impulses 61 by the differentiator 39. These impulses are rectified by a pair of rectifiers so that two groups of positive impulses 63, 50 65 are derived. One group is made up of variably spaced impulses 63 and the other of uniformly spaced impulses 65. Both groups of impulses are converted into dots or square wave form currents 67, 69. The currents of square wave form are 55 passed through filters which smooth out the wave form into varying currents 71, 73. One, 71, of these varying currents is phase or frequency modulated; the other, 73, is sinusoidal. These currents 71, 73 are impressed on the phase demodulation translator 53 to form a current 75 which represents the original signal and which actuates a loudspeaker or other signal indicator to thereby reproduce the signal.

The second receiving system, illustrated by Fig. 65 3, is comprised of a signal collector 77 which is attached to a receiver 79 comprising a tunable amplifier and a detector. The output circuit of the detector is connected to a limiter 81 which is in turn connected to a differentiator 83. The 70 output circuit of the differentiator is coupled to a rectifier 85. The rectifier 85 is connected to a dot reconstructer 87, whose output circuit is connected to a tuned circuit 89 which is in turn connected to a second rectifier 91. The output of 75

this rectifier 91 includes a signal indicating instrument 93.

The operation of the second receiving system is essentially as follows: The impulse modulated carrier waves 95 induce currents in the antenna which are selectively amplified and detected by the receiver 19. The rectified or detected currents are limited to eliminate excessive static or like impulses. The limited modulation currents 99 are converted into discrete impulses 101. These impulses are rectified to form a single group of positive impulses 103 which are variably spaced. The variably spaced impulses 103 actuate a dot reconstructor which converts 15 impulses into currents which have a square wave form 105. By impressing these currents 105 on a circuit 89, which is suitably tuned just off resonance, the frequency modulated currents may be converted into amplitude modulated currents, as 20 indicated by reference numeral 107. The amplitude modulated currents 107 are again rectified, and the thus rectified currents 109 impressed on a signal indicating instrument 93, which reproduces signals substantially equivalent to the original signals.

Having described the general method of transmitting and receiving, I shall briefly describe some of the component parts. Inasmuch as there are numerous devices which will create the desired effects, it should be understood that the following components are set forth by way of example rather than limitation.

The microphone 1 and amplifier 3 may be any of the conventional devices well known to those skilled in the art. In Fig. 4 is illustrated a carrier frequency generator which is comprised of a piezo-electric crystal 111 which is connected to the input circuit of a thermionic tube 113. The output circuit of this tube 113 includes a tunable circuit 115 and output circuit terminals 117.

The phase modulator, represented in Fig. 5, comprises an audio input transformer 119. The secondary terminals of transformer 119 are connected to the one set of grid electrodes 120, 122 of thermionic tubes 121, 123. The mid-tap of the transformer 119 is connected through a suitable bias means 125 to the cathodes of the tubes 121, 123. The anode electrodes are connected together and to a resonant circuit 127 which is connected to the anode current source 129. A second set of grid electrodes 131, 133 are respectively coupled to tuned circuits 135, 137 which are resonant to the carrier currents. The carrier currents are impressed on the tuned circuits 135, 137 in 90° phase relationship, through suitable coupling means 139. The second set of grid electrodes 131, 133 may be biased either positively or negatively, depending upon the type of tubes and the tube characteristics. The output circuit of the phase modulator is represented by an output circuit 141.

The impulse generators 7 are each represented by Fig. 6, and are constituted as follows: A current limiter 143, which may be a pair of suitably biased resistance coupled thermionic tubes 145, 147. The output of the current limiter is applied to a differentiator comprising a serially connected capacitor 149 and resistor 151. The input bias voltage of the first tube 145 is adjusted to normally prevent anode current from flowing in the anode circuit of the first tube 145. The second tube 147 is adjusted to permit full anode current to flow. As the input voltage across the input terminals of the first tube is increased, a potential will be reached at which anode cur-

rent will flow in the first tube 145. The current in the anode resistor of the first tube 145 places a negative grid bias on the second tube 147 which tends to block currents in the anode circuit of the second tube 147. Thus the limitation is obtained and, as an incident, these tubes 145, 147 may also amplify.

The differentiator, comprising the capacitor 149 which has a relatively high reactance with respect to the resistance of the resistor 151, acts on the output currents of the limiter 143 to produce discrete, sharply peaked impulses. The impulses are impressed on the input circuit of a thermionic tube 153 which is biased to cut off its anode current, thereby making the tube 153 only responsive to the applied positive impulses. These impulses may be used to directly key a transmitter whereby variably timed and uniformly timed impulses may be sent out, or they may be used to operate an impulse relay.

One form of impulse relay is represented schematically in Fig. 7. The impulse relay employs a pair of thermionic tubes 155, 157 which are connected as a multi-vibrator. The multi-vibrator is adjusted so that it has a free frequency of the order of the carrier frequency, and is controlled by impressing the positive impulses, of uniform and variable timing or spacing, on the input circuits. The uniformly spaced impulses are impressed on the input 159 of one, 30 155, of the pair of tubes, and the variably spaced impulses are impressed on the input 161 of the other, 157, of the pair of tubes. The output circuit of the impulse relay is represented by reference numeral 163.

The output circuit of the impulse relay is connected to key a conventional radio transmitter, which is illustrated schematically in Fig. 8. A thermionic oscillator 165 is arranged with a resonant input circuit 167 and a resonant output 40 circuit 169. The input circuit includes terminals 171, which are connected to the keying source. The output circuit 169 is suitably coupled to an antenna 173, from which the impulse modulated carrier wave is radiated.

The receiving system is comprised of the following units: A signal collecting antenna which is connected to the input of a conventional radio receiver, such as a tuned radio frequency amplifier and detector, a superheterodyne or the like. Such receivers require no detailed description, as they are well known to those skilled in the art. The detector output is impressed on a limiter, such as was described in connection with Fig. 6.

The differentiator circuit 39 for the receiving system is somewhat different from the differentiator used in the transmitting system. The present differentiator is shown schematically in Fig. 9, which includes a pair of rectifiers. The input circuit 175 includes a resistor 177 and a portion of the inductor 179 which is tapped at a point intermediate its ends. The tap is connected through a bias means 181 to the cathodes of a pair of rectifiers 183, 185. The signal grids 65 of these tubes are connected, respectively, to the ends of the inductor 179. The screen grid electrodes may be biased positively with respect to the cathodes by a connection to the anode current source 187. The anode electrodes are connected through a pair of resistors 189, 191 to the positive terminal of the anode current source. The output circuit includes connections to each anode and to the junction of the resistors. The combination of the differentiator and the pair 70 75

of rectifiers first converts the currents of square wave form into discrete positive and negative impulses, corresponding, respectively, to increasing and decreasing limiter output, and then rectifies these impulses so that the two groups of positive impulses 63, 65 are derived in the output circuit of the rectifiers.

The two groups of positive impulses are reconstructed into two currents of square wave form by the dot reconstructor apparatus shown in Fig. 10. This circuit is characterized by the fact that alternate input impulses start and stop the current flow in the output circuit. This feature has been disclosed and claimed in my copending application entitled "Impulse operated relay", Serial No. 47,675, filed October 31, 1935. The input circuit 193 is connected to the grid electrode of a gas filled relay tube 195. The relay tube is self-biased and protected by a resistor 197. The voltage drop across this resistor 197 is impressed on the input circuit of a thermionic tube 199. A variable capacitor 201 is shunted across the output circuit of the gas filled relay tube. The anode circuits of both tubes 195, 199 are respectively completed by resistors 203, 205. The output of the dot reconstructor includes the latter resistor 205 and a blocking capacitor 207.

The pair of dot reconstructors 43, 45 are connected to a wave shaping network which is shown in Fig. 11. The input circuit of the filter is composed of a resonant circuit 209. The output circuit of the filter is composed of a second resonant circuit 211. The two resonant circuits are coupled by any suitable type of mutual coupling, such as M. The degree of coupling is one of the factors which determine the relation width of the frequency band which the filter will pass. The effect of the filter is to re-shape a square wave form 67, 69 to a sinusoidal wave 71, 73 (see Fig. 2).

The output of the filters 47, 49 is impressed on a phase modulation translator 51. One suitable form of translator is shown in the schematic circuit diagram of Fig. 12. The input circuits of thermionic tubes 213, 215 are connected in push-pull to the filters. The anode circuits of these tubes 213, 215 are connected together through the signal reproducer 217 to the positive terminal of the anode battery 219 which is connected to the junction 221 of the cathode electrodes.

The second receiving system, shown in Fig. 3, employs component parts which are essentially similar to the first receiving system, with the following modifications: A single rectifier 85 and single dot reconstructor 87 are used in place of the pair of rectifiers 41 and pair of dot reconstructors 43, 45. The filters 47, 49 may be replaced by a conventional tuned circuit 89 which is comprised of an inductor and a capacitor. The tuned circuit is adjusted just off resonance to convert the frequency modulated wave into an amplitude modulated wave. The phase modulation translator 51 is replaced by a single rectifier 91 and signal indicator 93.

In the several systems multi-purpose tubes may replace separate tubes. In both receiving systems, the limiters 37, 81 may be eliminated, although I prefer to use limiters for the obvious improvement in signal-to-static ratio. In the foregoing specification I have described the apparatus for and the method of generating a carrier current which is divided into a sinusoidal reference current and a phase modulated current. These currents are converted into two

groups of discrete impulses, one of which is uniformly spaced and the other is variably spaced. These impulses may be used either to directly key a transmitter, or may be converted into currents of square wave form which key the transmitter. The transmitted impulse or dot modulated wave is received and reconverted into phase modulated currents which are translated to reproduce the signal currents.

I claim as my invention:

1. In a system of the character described, means for phase modulating a locally generated oscillation by a signal representing current, a local oscillator for generating constant frequency carrier currents, means for converting said phase modulated currents and said carrier frequency currents into two series of positive impulses, and means for transmitting said series of positive impulses.

2. In a system of the character described, means for phase modulating a locally generated oscillation by a signal representing current, a local oscillator for generating constant frequency carrier currents, means for converting said phase modulated currents and said carrier frequency currents into a series of phase modulated positive impulses, a radio wave transmitter, and a relay controlled by said impulses for keying said transmitter.

3. The method of transmitting a radio wave which consists in phase modulating a carrier current by a signal representing current, generating a constant frequency carrier current, applying said modulated and said carrier currents to the input of a generator of positive impulses, applying the so generated impulses to start and stop the flow of a local source of current, and applying such local currents to key a transmitter.

4. The method of transmitting a radio wave which consists in phase modulating a carrier current by a signal representing current, generating a constant frequency carrier current, applying said modulated and said carrier currents to the input of a positive impulse generator, and keying a transmitter with said positive impulses.

5. In a system of the character described, means for generating a constant frequency carrier current, means for phase modulating said current with signal representing currents, means for converting said modulated current and said carrier current into discrete impulses, means for converting said discrete impulses into currents of square wave form, and means actuated by said currents of square wave form for keying a transmitter.

6. In a system of the character described, means for generating a constant frequency carrier current, means for phase modulating said current with signal representing currents, means for converting said modulated current and said carrier current into discrete impulses which are respectively variably spaced and uniformly spaced, means for converting said discrete impulses into currents of square wave form, and means actuated by said currents of square wave form for keying a transmitter.

7. In a system of the character described, means for generating a constant frequency carrier current, means for phase modulating said current with signal representing currents, means for converting said modulated current and said carrier current into discrete impulses which are respectively variably spaced and uniformly

spaced, and means actuated by said discrete impulses for keying a transmitter.

8. In a system of the character described, means for generating a constant frequency carrier current, means for phase modulating said current with signal representing currents, means for converting said modulated current and said carrier current into discrete impulses, means for converting said discrete impulses into currents of square wave form, means actuated by said currents of square wave form for keying a transmitter, means for radiating signal waves from the said keyed transmitter, means for receiving said waves, and means for converting said waves into signal representing currents.

9. In a system of the character described, means for generating a constant frequency carrier current, means for phase modulating said current with signal representing currents, means for converting said modulated current and said carrier current into discrete impulses which are respectively variably spaced and uniformly spaced, means actuated by said discrete impulses for keying a transmitter, means for radiating signal waves from the said keyed transmitter, and means for converting said waves into signal representing currents.

10. The method of signaling which comprises generating a constant frequency carrier current, modulating a portion of said current by signal currents to form a phase modulated current, converting said phase modulated portion into discrete positive impulses, converting said unmodulated portion of carrier current into discrete positive impulses, and applying said impulses to control the transmission of carrier waves.

11. The method of signaling which comprises generating a constant frequency carrier current, modulating a portion of said current by signal currents to form a phase modulated current, converting said phase modulated portion into discrete positive impulses, converting said unmodulated portion of carrier current into discrete positive impulses, converting said positive impulses into currents of square wave form, and applying said currents of square wave form to control the transmission of carrier waves.

12. In a receiver of the character described, a radio receiver including a detector, means for differentiating currents derived by said detector,

means for rectifying said differentiated currents to obtain discrete unidirectional impulses, means for converting said rectified impulses into currents of square wave form, means for shaping said square wave form currents into gradually varying currents, and means for translating said currents into signal representing currents.

13. In a device of the character of claim 12, means for limiting said detected currents.

14. In a device of the character of claim 12, means for translating said signal representing currents into discernible signals.

15. The method of receiving modulated carrier currents of the character described which comprises amplifying and detecting said carrier currents, differentiating said currents to form discrete impulses, rectifying said impulses, converting said rectified impulses into currents of square wave form, shaping said square wave form currents into gradually varying currents, and translating said gradually varying currents into signal representing currents.

16. The method of receiving modulated carrier currents of the character described which comprises amplifying and detecting said carrier currents, limiting said currents, differentiating said currents to form discrete impulses, rectifying said impulses, converting said rectified impulses into currents of square wave form, shaping said square wave form currents into gradually varying currents, and translating said gradually varying currents into signal representing currents.

17. The method of receiving modulated carrier currents of the character described which comprises amplifying and detecting said carrier currents, differentiating said currents to form discrete impulses, rectifying said impulses to form groups of uniformly spaced and variably spaced impulses, converting said uniformly spaced impulses and said variably spaced impulses into two separate currents of square wave form, filtering said two currents to obtain gradually varying currents, and translating said gradually varying currents into signal representing currents.

18. The method of receiving modulated currents described by claim 17 and comprising the additional step of limiting said currents after their detection.

DAVID G. C. LUCK. 50
